(57) **ABSTRACT**

'FLR14-372' is a new and distinct southern highbush blueberry (*Vaccinium corymbosum* L.) variety distinguished by a low chilling requirement, semi-upright growth habit, and firm, crunchy, and early-maturing fruit that are sweet and aromatic with a small, dry picking scar.

5 Drawing Sheets

1

Latin name of the genus and species of the plant claimed:
Vaccinium corymbosum L.

Variety denomination: 'FLR14-372'.

CROSS REFERENCE TO RELATED APPLICATIONS

This application claims the benefit of European Community Plant Breeders Rights Appl. No. 20191682, filed Jul. 9, 2019, herein incorporated by reference in its entirety.

BACKGROUND OF THE INVENTION

The present invention relates to a new and distinct hybrid variety of southern highbush blueberry (*Vaccinium corymbosum* L.) named 'FLR14-372'. 'FLR14-372' is a blueberry clone distinguished by its very low chilling requirement, very good performance when grown in an evergreen production system, very early ripening, and firm berries with excellent flavor. Several thousand plants of 'FLR14-372' have been propagated and established in Lalla Mimouna, Morocco, and the resulting plants have all been phenotypically indistinguishable from the original plant.

2

'FLR14-372' originated as a seedling from a cross between 'Snowchaser' as the female (seed) parent and 'FL04-174' (unpatented) as the male (pollen) parent. This cross was made in Lalla Mimouna, Morocco in 2014. The seedling was planted in a high-density field nursery in 2015 and the first fruit were evaluated during the same year. Due to its early fruit production and excellent fruit quality, 'FLR14-372' was selected and first asexually propagated in Lalla Mimouna, Morocco by softwood stem cuttings. In 2016, an experimental 10-plant test plot was established as part of a variety test in Lalla Mimouna Morocco. Based on the growth, yield, and fruit quality of this plot, 'FLR14-372' was repropagated by softwood stem cuttings and in 2017 experimental test plots were established at two other farms in Morocco. These plots have been observed during flowering and ripening each year, and no mutations or off-type plants have been observed.

'Snowchaser' (U.S. Plant Pat. No. 19,503) is an important southern highbush blueberry variety widely planted in the United States. 'FLR14-372' is believed to be most similar to 'Snowchaser'. Nonetheless, 'FLR14-372' and 'Snowchaser' are distinguishable at least in their fruit production, pedicel length at time of anthesis, leaf shape, and leaf pubescence at the margins. Specifically, the claimed plant produces fruit

six weeks earlier than 'Snowchaser'. The fruit of 'FLR14-372' is also consistently firmer than the fruit of 'Snowchaser' throughout the harvest season. Additionally, 'FLR14-372' exhibits a longer pedicel length at time of anthesis, and an elliptic leaf shape with an absence of leaf pubescence at the margins, while 'Snowchaser' exhibits a shorter pedicel length at time of anthesis, and an ovate leaf shape with sessile glands along the margins of the leaf blade.

Similar to 'FLR14-372', 'FLR12-89' (U.S. patent application Ser. No. 16/923,952) is another southern highbush blueberry variety that is both characterized by very early fruit ripening, and originated from 'Snowchaser' as the female (seed) parent. Nonetheless, plants of 'FLR14-372' and 'FLR12-89' can be readily and unambiguously distinguished from one another at least based upon their internode length, flower clusters, and berry characteristics. Specifically, 'FLR14-372' exhibits shorter internode length, medium flower clusters; and berries having a crunchy texture and a very strong aroma flavor, whereas 'FLR12-89' exhibits longer internode length, tight flower clusters, and berries having a smooth texture and lacking a strong aroma flavor. Also, plants of 'FLR12-89' display a growth habit that is more compact than plants of 'FLR14-372'.

SUMMARY OF THE INVENTION

Blueberry variety 'FLR14-372' exhibits outstanding and distinguishing characteristics when grown under normal horticultural practices in Lalla Mimouna, Morocco, including: (1) a very low chilling requirement; (2) very good performance as an evergreen plant; (3) very early fruit ripening; and (4) firm berries with an excellent, aromatic flavor.

BRIEF DESCRIPTION OF THE DRAWINGS

The accompanying photographs show typical bush, flower, and fruit characteristics for 'FLR14-372'. Colors shown are as true as can be reasonably reproduced by photographic procedures and may differ from those cited in the detailed description, which accurately describes the colors of 'FLR14-372'.

FIG. 1—Shows several clusters of flowers of 'FLR14-372', as observed during the early stages of flowering.

FIG. 2—Shows branches with green fruit clusters of 'FLR14-372' during the fruit ripening period.

FIG. 3—Shows a close-up of ripe harvested 'FLR14-372' berries.

FIG. 4—Shows a close-up of mature 'FLR14-372' leaves with a scale bar.

FIG. 5—Shows several 'FLR14-372' plants when grown in an evergreen production system in Lalla Mimouna, Morocco.

DETAILED BOTANICAL DESCRIPTION

The following detailed description sets forth the distinctive characteristics of 'FLR14-372'. The data that define these characteristics were collected from asexual reproductions carried out in Morocco. The plants were 2 years of age when the data was collected. Certain characteristics may vary with plant age. Certain characteristics may vary with plant age. 'FLR14-372' has not been observed under all possible environmental conditions, and the measurements given may vary when grown in different environments. Where means are given, the sample size was 10. Color

descriptions are based on The Royal Horticultural Society (R.H.S.) Colour Chart by The Royal Horticultural Society, London, Fifth Edition, 2007. When the R.H.S. color designations differ from the accompanying photographs, the R.H.S. color designations are accurate.

PHENOTYPIC DESCRIPTION OF *VACCINIUM CORYMBOSUM* L. ('FLR14-372')

10 Plant:

Plant vigor.—High.

Growth habit.—Semi-upright.

Flower bud density (number) along flowering twigs in march.—Medium to High, averaging 11.4.

Twigginess.—High.

Tendency toward evergreeness.—High.

Productivity.—In trials in Morocco, 'FLR14-372' was very productive, with higher total yields than 'Snowchaser'.

Chilling requirement.—'FLR14-372' has performed best under evergreen production conditions where chilling is not calculated. 'FLR14-372' flowered and leafed well in areas receiving an average of 300 chill hours (0 to 7° C.).

Cold hardiness.—'FLR14-372' has not been grown in temperate climates with extremely cold winter temperatures. Plants have survived winter freezes of -2° C. without damage.

Ease of propagation.—In propagation by cuttings of softwood stems, 'FLR14-372' has a good percentage of rooting (90% success), superior to 'Snowchaser'. 'FLR14-372' has also a very good response to meristematic culture.

35 Trunk and branches:

Suckering tendency.—High. Plants typically average 27 canes (with observed number of canes ranging from a minimum of 24 to a maximum of 30) arising from the crown.

Surface texture (of strong, 6-month-old shoots observed in march).—Smooth.

Surface texture (of 3-year-old and older wood).—Rough.

Color of new twigs observed in the field.—Yellow-green N144D.

Color of 3-year-old, rough-textured canes.—Greyed-brown N199C.

Internode length (strong, upright shoots measured in march).—Mean of 24.1 mm.

50 Leaves:

Length (including petiole, from tip of petiole to end of blade).—Mean of 8.1 cm.

Width (at widest point).—Mean of 3.4 cm.

Shape.—Elliptic.

Margin.—Entire.

Color.—Upper surface: Green N134B. Lower surface: Yellow-green N147B.

Pubescence.—Upper surface of leaves: Absent. Lower surface of leaves: Absent. Margins: Absent.

Relative time of leafing versus flowering.—When grown as an evergreen plant, leafing is delayed relative to flowering.

Flowers:

Arrangement.—Flowers are arranged alternately along a short, leafless, deciduous branch.

Fragrance.—Strong floral fragrance.

<i>Shape</i> .—Urceolate.	Berry:
<i>Flowering period</i> .—The bloom period when observed under evergreen production in Morocco is from September to December.	
<i>Cluster (tight, medium, loose)</i> .—Medium.	<i>Cluster (tight, medium, loose)</i> .—Medium.
<i>Number of flowers per cluster</i> .—Mean of 8.4.	<i>Weight (on well-pruned plants)</i> .—Mean of 1.8 grams.
<i>Pedicel</i> .—Length at time of anthesis: Mean of 11.0 mm. Color at time of anthesis: Yellow-green 144D with greyed-red 180C on the sun-exposed side.	<i>The first harvested fruits average roughly 3 grams.</i>
<i>Peduncle</i> .—Length at time of anthesis: Mean of 17.3 mm. Color at time of anthesis: Green 142C with greyed-red 179A on sun-exposed side.	<i>Height</i> .—Mean of 12.8 mm.
<i>Calyx</i> .—Surface texture: Smooth. Diameter: Mean of 7.6 mm. Color (outer surface, visible at the time of anthesis without removing the corolla tube): Green 138C to Red 47B on calyx lobes.	<i>Width</i> .—Mean of 17.0 mm.
<i>Corolla</i> .—Diameter: Mean of 7.4 mm. Length (from pedicel attachment point to corolla tip excluding the pedicel): Mean of 7.9 mm. Aperture diameter: Mean of 5.0 mm. Texture: Smooth. Color: White 155B.	<i>Shape</i> .—Oblate.
<i>Reproductive organs</i> :	<i>Surface color of mature berries ripe on the plant</i> .—Violet-blue 98D.
<i>Style</i> .—Length (top of ovary to stigma tip): Mean of 7.6 mm. Color: Yellow-green 145B. Location of tip of stigma relative to lip of the corolla — Stigma tip is approximately even to 1 mm outside the corolla lip.	<i>Surface color of ripe berry after polishing</i> .—Greyed-purple N186A.
<i>Anthers</i> .—Color: Greyed-orange N167B. Pollen — Abundance of shed: Medium. Color: Orange-white 159B.	<i>Immature berry color, with bloom</i> .—Greyed-green 193B.
<i>Self-fruitfulness</i> .—Low to medium. Planting in field configurations that promote cross fertilization with other southern highbush varieties is recommended for all southern highbush blueberry plants.	<i>Immature berry color without bloom</i> .—Yellow-green N144C.
<i>Fruit</i> :	<i>Surface wax</i> .—Medium to high. The surface wax on 'FLR14-372' has only moderate persistence.
<i>Mean date of 50% harvest in Lalla Mimouna, Morocco</i> .—February 25.	<i>Pedicel scar</i> .—Small and dry. Mean of 2.7 mm.
<i>Diameter of calyx aperture on mature berry</i> .—Mean of 10.1 mm.	<i>Firmness</i> .—Very firm.
<i>Size and shape of calyx lobes on mature berry</i> .—Small and very erect.	<i>Flavor</i> .—Sweet with a very strong aroma.
<i>Pedicel length on ripe berry</i> .—Mean of 11.8 mm.	<i>Texture</i> .—Crunchy.
<i>Detachment force for ripe berries (easy, medium, hard)</i> .—Hard on the first fruits, but easy during the full harvest.	<i>Seeds</i> :
<i>Number of berries per cluster</i> .—Mean of 7.9.	<i>Color of dried seeds</i> .—Greyed-orange N167A.
<i>Fruiting type</i> .—On one-year-old and current season's shoots.	<i>Length of well-developed dried seed</i> .—Mean of 1.8 mm.
	<i>Width of well-developed dried seed</i> .—Mean of 1.0 mm.
	Use: 'FLR14-372' produces southern highbush blueberries suitable for fresh markets. 'FLR14-372' has performed best in trials when grown under an evergreen management system.
	Resistance to diseases, insects, and mites: 'FLR14-372' has grown vigorously and shows excellent bush survival when grown under protected cultivation in an evergreen management system. It appears to be moderately resistant to root rot (<i>Phytophthora cinnamomi</i>). 'FLR14-372' appears to have excellent resistance to the fungal species that cause summer leaf spots. Resistance of 'FLR14-372' to fungal leaf spots, <i>Botrytis</i> fruit rot, and powdery mildew (<i>Microsphaera vacciniae</i>) is greater than that of 'Snowchaser', although we could observe under certain conditions a low sensitivity to powdery mildew (<i>Microsphaera vacciniae</i>).
	What is claimed is:
	1. A new and distinct variety of southern highbush blueberry plant named 'FLR14-372', as illustrated and described herein.
